UNITED STATES PATENT OFFICE.

WILLIAM L. M. ROBIDOUX, OF PAWTUCKET, RHODE ISLAND.

CORD-FASTENING HOOK.

1,419,410.

Specification of Letters Patent. Patented June 13, 1922.

Application filed April 6, 1922. Serial No. 550,108.

To all whom it may concern:

Be it known that I, WILLIAM L. M. ROBIDOUX, a subject of the King of England, residing at Pawtucket, in the county of Providence and State of Rhode Island, have invented certain new and useful Improvements in Cord-Fastening Hooks, of which the following is a specification.

This invention relates to improvements in 10 cord-fastening hooks adapted for use as a lacing fastener for shoes and also for fastening the ends of cords or lines such as clothes lines, and other cords and lines, and the object of this invention is to provide 15 such a hook having a shank portion with a base-flange and guide flange and a head-member, the guide flange having a portion extending beyond the periphery of the flange less than one diameter of the cord 20 whereby the drawing of a second turn of the cord about the shank of the hook forces the first turn to ride up over the guide flange and cross the second turn to automatically bind that part of the second turn at the point 25 of crossing.

With these and other objects in view, the invention consists of certain novel features of construction, as will be more fully described, and particularly pointed out in the 30 appended claims.

In the accompanying drawings:

Figure 1 is a front view showing a portion of a shoe with the ends of the lacing secured by being locked in my improved fastening 35 hook.

Figure 2 is an enlarged top view of my improved hook.

Figure 3 is a side elevation of the hook showing a tubular shank adapted to be applied to a shoe-upper for receiving and securing the end of the lacing.

Figure 4 is a side elevation of an enlarged fastening hook adapted more particularly to be applied to a suitable base such as the 45 side of a house and the like to which the end of a clothes line may be attached.

Figure 5 is a section on line 5—5 of Figure 4, looking in the direction of the arrow and showing the counter-sunk holes formed 50 in the base-flange to receive the attaching screws.

Figure 6 is a top view sectioned on line 6—6 of Figure 5, showing the cord as applied to the hook, one portion of the cord

being bound to the hook by the passing of 55 another portion of the cord thereover.

Figure 7 is a perspective view showing one portion of the cord as crossing and binding another portion thereof, the crossing portion being engaged by the notch in the 60 guide-flange.

It is found in practice to be of advantage to be able to produce a lacing-hook or cord-fastening hook of a simple and practical construction that will secure and bind the 65 end of a cord or lacing therein by simply winding the part twice around the hook and drawing the end taut, which construction is of advantage either as a hook to be applied to shoes for securing the end of a lacing, or 70 as a hook of a larger size to be applied to a suitable base to which the end of a cord or line may be fastened by simply taking a second turn about the hook and drawing the same taut, and the following is a detailed 75 description of one means by which this result may be accomplished:—

To accomplish the fastening of a cord to the hook automatically the hook must be set so that the angle of lead of the cord as 80 shown in Figures 1 and 6, will be such as to cause the first coil or turn of the cord to slide into the space beneath the head and be drawn up against the bridge portion thereof upon being forced or raised out of 85 the lower groove by the drawing or laying of the second turn of the cord thereinto.

With reference to the drawings, 10 designates the shank portion of the hook which is provided with a base-flange 11, and at the 90 outer end of this shank is mounted a guide-flange 12 spaced above the flange 11 substantially one diameter of the cord which the hook is designed to receive.

This guide-flange is provided with a rearwardly-extending neck portion 13 from which rises a bridge-member 14 supporting a head 15 which extends back over the guide-flange, being spaced approximately one diameter of the cord above said flange.

The guide-flange 12 is preferably elongated on its sides as at 16 providing hook-shaped edges 17 having its rear edge undercut or notched as at 18 forming a recess for the reception of a portion of the cord 19. This recess or undercut portion being preferably formed on opposite sides of the post so as to permit the hook to be used either as a right

or left handed fastener, as illustrated in Figure 1, the outside notch, or that one on the side of the hook opposite the lead of the cord being, however, the only one generally used 5 in effecting a fastening of the cord end.

In order to insure the sliding or lifting of the first turn of the cord up over this flange, as the second turn of the cord is passed around the post to crowd or force the first 10 turn outwardly I have preferably reduced the overhanging edge portion of this flange at the front of the hook as at 20 or that portion opposite the bridge 14, whereby the first turn is caused to normally lie in the space 15 between the base-flange and the guide-flange until the second turn is made, which second turn is caused to crowd the first turn of the cord and force it up over the narrow lip 20 into the space between the guide-flange and 25 the head and a continued pulling or slipping of the cord carries the raised part of the cord outwardly to be drawn against the bridge 14 and over into the notch 18, which notch serves to assist in locking the cord at the 30 point of crossing to positively prevent the free end from becoming withdrawn by any tension applied to the opposite end thereof.

The device is extremely simple and practical in construction and effective in its action and by its use when properly set relative to the lead of the cord, it is only necessary to pass the cord twice around the shank of the fastener and by drawing tightly on the free end of the second turn it will automatically force the first turn out of its original position to cross the second turn and so 35 securely lock the end in the hook.

The foregoing description is directed solely towards the construction illustrated, but I

desire it to be understood that I reserve the 40 privilege of resorting to all the mechanical changes to which the device is susceptible, the invention being defined and limited only by the terms of the appended claims.

I claim:

1. A cord-fastening hook comprising a shank having a base-flange, a guide-flange on said shank spaced from said base-flange substantially one diameter of the cord and having a portion extending beyond the periphery of said shank less than one diameter of the cord, and a head connected to and spaced from said guide flange substantially one diameter of the cord whereby the drawing of a second turn of the cord about said shank 50 forces the first turn to ride up over the guide-flange and across the second turn to automatically bind the second turn at the point of crossing.

2. A cord-fastening hook comprising a 60 shank having a base-flange, a guide-flange on said shank spaced from said base-flange substantially one diameter of the cord and having a portion extending beyond the periphery of said shank less than one diameter 65 of the cord and provided with a notch on its side edge, and a head member connected to the rear of said guide-flange by a bridge portion whereby the drawing of a second turn of the cord about said shank forces the first 70 turn to ride up over said guide-flange into said notch to lie against said bridge and cross the second turn to automatically bind that part of the second turn at the point of crossing.

In testimony whereof I affix my signature.

WILLIAM L. M. ROBIDOUX.
